UNITED STATES PATENT OFFICE.

JONATHAN PETERSON, OF BROOKLYN, NEW YORK, ASSIGNOR TO COMBINATION MANUFACTURE COMPANY, OF NEW YORK, N. Y., A CORPORATION OF DELAWARE.

CAN OR BOX LID.

Application filed March 8, 1926. Serial No. 93,140.

My invention relates to improvements in can or box lid or cover structures.

In the present specific example the invention is embodied in a lid for snuff boxes and particularly a lid having a spoon formation; but the invention is not necessarily limited to such uses nor is the lid structure necessarily provided with a spoon formation.

In certain respects the present invention is an improvement upon that described in patent to me, No. 1,344,650, of April 29, 1920, which disclosed a pressed sheet metal lid adapted for snuff boxes or cans and having a spoon formation as a convenience to the user in dipping snuff from the box and utilizing the amount so dipped in the ways employed by snuff users, without wastage involved in pouring the snuff from the box, or other ways of utilizing snuff theretofore employed. The lid disclosed in said patent, is, however, relatively difficult and expensive to manufacture, since it is made of a single piece of sheet metal and the formations are relatively deep and require difficult and expensive pressing or stamping operations.

An important object of the present invention is to improve upon the lid disclosed in said patent by forming it in two pieces instead of one. By this means the spoon and other formations may be more easily and cheaply produced and especially the pressing operations are simplified. At the same time the lid is so formed that it materially reinforces the can to which it is applied, as more fully explained hereafter.

The characteristics and advantages of the invention are further sufficiently explained in connection with the following detail description of the accompanying drawing, which shows one representative embodiment of the invention. After considering this example, skilled persons will understand that many variations may be made, and I contemplate the employment of any structures that are properly within the scope of the appended claims.

In the drawings:

Fig. 1 is a perspective view of a can lid, embodying the invention in one form, shown in position on a can for which it is adapted.

Fig. 2 is a section at 2-2, Fig. 1.

Fig. 3 is a fragmentary section (of the upper part of the can and the complete lid) at 3-3, Fig. 2.

Fig. 4 is a composite perspective view of

the two lid parts disconnected but in approximate positions for connection or assembly.

In the present specific embodiment of the invention the lid L is adapted to a sheet metal snuff can C having flat parallel side walls 1, rounded ends 2, a bottom 3 and a top edge 4 above the bead 5, this bead usually being provided for decorative appearance and to stiffen the wall structure, although it is not essential, so far as the present lid is concerned. The can body including walls 1 and 2 may sometimes be of cardboard or other material and in such cases the bottom 3 may be of sheet metal and secured to the body in any convenient way.

The lid comprises an outer or top member T and an inner or bottom member B. Each of these members or parts is of pressed sheet metal. The top has its outer wall 10 of a contour conforming to the plan contour of the can. The wall 10 is bent at the margin to form a peripheral wall or lip 11, the ends 12 of which are usually relatively shallow. A spoon or bowl 13 is formed in one end portion of the top 10.

The inner or bottom section B comprises a main or bottom wall 15, usually with upwardly sloping end portions 16, and a peripheral wall 17, the end portions 18 of which are relatively shallow to correspond with the shallow ends 12 of the top member 10. Along the major part of the length of each side wall 17, at the upper edge thereof, the material is bent outward to provide a flange 19, and a shallower flange or lip 20 may be continued about the remainder of the side and end wall contour.

The top and bottom sections may be secured together in various ways, for example, by spot welding along the lines of the flanges 19 or the narrow margins or lips 20 where these parts engage the inner surface of the top section; otherwise the two parts are sufficiently connected by engagement of the flanges 19 in beads 25, as fully explained hereafter.

The flanges 19 fit in longitudinal recesses or sockets 25 pressed or swaged outwardly in the side walls 11 of the top section T where these side walls adjoin the top wall 10. These socket or concave formations at the inside of the top structure produce convex beads or ribs at the outside, as best shown in Figs. 1 and 4. The formations 19 and 25

may be produced on the independent parts or may in some cases be formed as the parts are pressed together. In either case the completed lid consists of the top and bottom sections T and B interlocked, as shown in Fig. 3, by the flanges 19 fitting in the longitudinal beads or sockets 25. The walls 17 and 18 of the bottom section are then spaced somewhat away from the adjacent walls 11 and 12 of the top section, permitting the upper wall margin 4 of the can to be located in the space thus provided. By this arrangement the can is materially reenforced when the cover is in position, since the walls 17 of the inner lid section B confront the flat side walls of the can and prevent them from being bent inward. This is important, not only to preserve the shape of the can under pocket or other pressure, but because in the absence of such means, inadvertent bending of the side walls produces a bellows action, tending, when the can is filled with fine, dry snuff, to puff the snuff out through narrow interstices between the can rim and lid, with obvious objectionable results, as well as unnecessary loss of the material.

The spoon formation near one end of the lid is available for removal of small quantities of snuff from the can for use in any of the ways known to snuff users, by slightly tilting the lid after removal from the can and inserting the spoon end into the can, whereupon the desired quantity of snuff may be dipped up in the spoon and then applied for use in any of the known ways. The rounded formations of the lid adjacent the spoon prevent accidental injury to the face or fingers of the snuff user which might otherwise result from ragged edges adjacent to the spoon formation. Especially, the provision of a spoon or bowl with rounded contours obviates the use of an ordinary tin lid with ragged tin edges in lieu of a spoon or dipper. Use of such ordinary lids frequently causes cuts or scratches by contact of the raw edge with the face or fingers.

The flanges 19 on the bottom section B cooperate with the bead or socket formations 25, and not only serve to effectively lock these two lid sections together, but the beads 25 which are convex at the outside of the lid, provide a convenient finger grip to aid in removing the lid and also act to practically automatically direct the user to grasp the lid at the long sides and remove it by a straight pull or sidewise tilting, which avoids the greater risk of deforming the lid when it is tilted endwise in removal. As compared with previous structures, as illustrated in the patent above referred to, in which the lid is formed of a single pressed sheet, the present lid structure consisting of two pressed sheet members may be produced

with relatively simple and inexpensive pressing or swaging operations, and especially the deformation of the metal is not so deep or abrupt as in the other lid referred to, and therefore the present lid structure may be more efficiently and economically made.

The arrangement of the inner and outer cover walls 17, 18 and 11, 12, respectively, to provide a recess to receive the upper margin of the body, provides a very tight closure to securely retain the contents, which, in many cases, is dry finely pulverized snuff, and prevents this dust-like material from sifting out of the container when closed. The fit between the body and the lid walls may be even closer than shown in the drawings, which show slight clearance between these walls, for the sake of illustrative clearness. This tight or dust-proof closure is important, not only to prevent the waste of the contents, but annoyance caused by escape or sifting of the powder-like snuff into the pocket or upon the clothing of the user.

I claim:

1. A combined can lid and snuff dipper of oblong outline composed of a bottom and a top section, the sections flanged laterally and arranged with the flanges adjacent and with the flange of the bottom section fitting within the flange of the top section, the top section having at the long sides thereof opposite internal grooves at the junction of the flange with the body of the section, and the flange of the bottom section having extensions engaging within the grooves to connect the sections, the grooves providing external ribs at the long sides of the lid for engagement by the fingers to remove and replace the lid.

2. A combined can lid and snuff dipper of oblong outline composed of a bottom and a top section, the sections flanged laterally and arranged with the flanges adjacent and with the flange of the bottom section fitting within the flange of the top section, the top section having at the long sides thereof opposite internal grooves at the junction of the flange with the body of the section, and the flange of the bottom section having extensions engaging within the grooves to connect the sections, the grooves providing external ribs at the long sides of the lid for engagement by the fingers to remove and replace the lid, the top section having at one end a depressed spoon formation, and the ends of the bottom section inclining upwardly toward the top section to provide a lid having ends decreasing in thickness.

Signed at New York city in the county of New York and State of New York this 2nd day of May A. D. 1926.

JONATHAN PETERSON.
